UNITED STATES PATENT OFFICE.

WILLIAM MARK SEXSON, OF McALESTER, OKLAHOMA.

DESIGN FOR AN EMBLEM OR BADGE.

Application filed September 9, 1922. Serial No. 3,659. Term of patent 7 years.

To all whom it may concern:

Be it known that I, WILLIAM M. SEXSON, a citizen of the United States of America, residing at McAlester, in the county of Pittsburgh and State of Oklahoma, have invented a new, original, and ornamental Design for an Emblem or Badge, of which the following is a specification, reference being had to the accompanying drawing, forming a part hereof.

The drawing is a front elevation of a badge showing my new design.

I claim:

The ornamental design for a badge or emblem, as shown.

WILLIAM MARK SEXSON. [L. S.]
